UNITED STATES PATENT OFFICE

HENRY FUHRY, OF MILWAUKEE, WISCONSIN, ASSIGNOR OF ONE-HALF TO BLUMENFELD, LOCHER CO., OF MILWAUKEE, WISCONSIN, A CORPORATION OF WISCONSIN.

DEVICE FOR CUTTING FABRICS.

1,143,594.

Specification of Letters Patent. Patented June 15, 1915.

Application filed October 12, 1914. Serial No. 866,244.

To all whom it may concern:

Be it known that I, HENRY FUHRY, a citizen of the United States, residing at the city of Milwaukee, county of Milwaukee, and State of Wisconsin, have invented new and useful Improvements in Devices for Cutting Fabrics, of which the following is a specification.

My invention relates to improvements in devices for cutting fabrics, and it pertains more especially to that class of machines which are used for cutting trimmings or foundations used in the manufacture of hats.

15 My invention is explained by reference to the accompanying drawings in which,

Figure 1 is a side view part in vertical section drawn on line x, x of Fig. 2. Fig. 2 is a top view of the device shown in Fig. 1. 20 Fig. 3 is an end view, part in vertical section, as indicated in dotted lines y, y of Fig. 1. Fig. 4 is an end view similar to that shown in Fig. 3, showing the lifting cam in reversed position. Fig. 5 is an enlarged detail in vertical section drawn on the line z, z of Fig. 4.

Like parts are identified by the same reference numerals throughout the several views.

30 By my improved device for cutting fabrics, I employ two circular cutting blades 1 and 2. The cutting blade 1 is revolvably supported from the shaft 3, by and between the arms 4, 4, and said arms are rigidly connected with the vertical movable bar 5, and said bar 5 is slidably supported from the arm 6 in the head 7. Said bar 5 is provided with a transverse pin 8 and an eccentric cam 9. The eccentric cam 9 is pivotally supported from the upper end of the bar 5 by the bolt 10. Thus it will be obvious that when the eccentric cam 9 is in the position shown in Figs. 1 and 3, the bar 5 is drawn upward, whereby the cutting blade 1 is separated from and raised at quite a distance above the cutting blade 2, as shown in Fig. 1. When, however, the eccentric cam 9 is thrown in the reversed position, shown in Fig. 4, the cutting blade 1 is forced downwardly by the recoil of the spiral springs 11. The spiral springs 11 are interposed between the upper end of the head 7 and the pin 8, and said springs are adapted by their recoil to force said cutting blade 1 down 50 with a quick positive movement, whereby

the cutting edges of the two opposing blades 1 and 2 are caused to slightly over-lap each other, as shown in Fig. 5. When a fabric is brought between said blades 1 and 2, it is severed by the action of said blades. The 60 blade 2 is rigidly affixed to the shaft 12 and is adapted to revolve with it, while the blade 1 is revolved solely by the action of the fabric passing beneath it as it is being severed. Supported upon the respective sides of the 65 blade 1 are two feed rollers 13 and 14, which are adapted to contact with the opposing feed rollers 15 and 16, which are rigidly secured to and carried by the shaft 12. The 70 surfaces of said feed rolls are preferably slightly serrated or roughened, as shown in Fig. 1, whereby the fabric is more readily drawn forward between them as they are revolved by the action of the shaft 12.

17 is a band wheel which is rigidly affixed 75 to the shaft 12, from which motion is communicated through said shaft to the cutting blade 2. It will be understood that the band wheel 17 may be driven either manually or by any other power in the ordinary manner. 80 Preparatory to inserting the fabric to be cut, the eccentric cam 9 is moved from the position shown in Fig. 4 to that shown in Fig. 3, whereby the cutting blade 1 and feed rolls 13 and 14 are raised quite a distance from the cutting blade 2 and feed rolls 15 and 16, whereby the fabric may be readily inserted between said rollers. When trimming a hat or cutting the crown it can 85 be inserted between the rollers, as indicated 90 by dotted lines in Fig. 1. When this is done the eccentric cam 9 is brought to the position shown in Fig. 4, whereby the cutting blade 1 and feed rolls 13 and 14 are brought to the position indicated in Fig. 5. When 95 this is done the shaft 12 is revolved, whereby the fabric is fed forward by the feed rolls 15 and 16 coöperating with the feed rolls 13 and 14, whereby the fabric is severed by the coöperation of the cutting blades 1 and 2. It will be understood that by thus 100 operating the cutting blades and feed rollers by the revoluble movement of the shaft 12 the operator is enabled to place a hat or any other fabric between such cutting 105 blades, while owing to the fact that the upper blade 1 and feed rolls 13 and 14 are revolved solely by the friction of the fabric as it passes between said cutting blades, it becomes unnecessary to connect the upper 110

cutting blade and feed rolls with any driving mechanism and the operator is thereby enabled to move the hat or other fabric to be acted upon with the greatest freedom between such cutting blades and feed rolls.

18 is the bed plate of the machine, which is preferably made narrow at its front end or at the end adjacent to the cutting blades, whereby the hat or other fabric may be 10 readily revolved around said bed plate as it is passed between said cutting blades.

19 is a handle, which is rigidly connected with the eccentric cam 9, whereby such cam is readily moved by the operator.

15 Attention is called to the fact that the arm 6 is unusually long whereby a large space is provided upon the table or platform 18 for the reception of the hat or other fabric which is being operated upon by the 20 cutting blades, while the vertical member of said arm 6, shown at the right in Fig. 1, is at a great distance from said cutting blades. This is very important as it often becomes necessary to revolve the hat upon said 25 supporting platform 18 as said cutting blades are operated.

Having thus described my invention, what I claim as new and desire to secure by Letters Patent, is—

30 1. In a device of the described class, the combination of two circular cutting blades, a driven shaft supporting one of said cutting blades, a stationary shaft supporting the other cutting blade, a vertically moving 35 bar for supporting said last named shaft, said last named blade being adapted to be revolved by the movement of the fabric which is being cut by said blades, means for revolving said revoluble shaft, and means 40 for raising and lowering said vertically moving bar.

45 2. In a device of the described class, the combination of two circular cutting blades, a driven shaft supporting one of said cutting blades, a stationary shaft supporting the other cutting blade, a vertically moving bar for supporting said last named shaft, said last named blade being adapted to be revolved by the movement of the fabric

which is being cut by said blades, a band 50 wheel rigidly connected to one end of said revoluble shaft, and means for raising and lowering said vertically moving bar.

3. In a device of the described class, the combination of two circular cutting blades, 55 a driven shaft supporting one of said cutting blades, a stationary shaft supporting the other cutting blade, a vertically moving bar for supporting said last named shaft, said last named blade being adapted to be 60 revolved by the movement of the fabric which is being cut, two feed rollers one supported upon the respective sides of each of said cutting blades, means for revolving said revoluble shaft, means for raising and 65 lowering said vertically moving bar, a long arm adapted to support one of said cutting blades above and at a distance from the opposite edge of the platform of the machine.

4. In a device of the described class, the 70 combination of two circular cutting blades, a driven shaft supporting one of said cutting blades, a shaft supporting the other cutting blade, a vertically moving bar for supporting said shaft, said last named blade 75 being adapted to be revolved by the movement of the fabric which is being cut, two feed rollers one supported upon the respective sides of each of said cutting blades, means for revolving said revoluble shaft, 80 means for raising and lowering said vertically moving bar, and a pair of springs connected with said vertically moving bar and adapted to hold the upper feed rolls and cutting blade in yielding contact with the lower feed rolls and cutting blade, a long arm adapted to support one of said cutting blades above and at a distance from the opposite edge of the platform of the machine, 85 all substantially as and for the purpose 90 specified.

In testimony whereof I affix my signature in the presence of two witnesses.

HENRY FUHRY.
